Inventor:

Burnham C. Stickney

UNITED STATES PATENT OFFICE.

BURNHAM C. STICKNEY, OF RUTHERFORD, NEW JERSEY, ASSIGNOR TO UNDERWOOD
TYPEWRITER COMPANY, OF NEW YORK, N. Y., A CORPORATION OF DELAWARE.

TYPEWRITING MACHINE.

Original application filed February 9, 1923, Serial No. 617,912. Divided and this application filed
January 7, 1925. Serial No. 969.

To all whom it may concern:

Be it known that I, BURNHAM C. STICKNEY, a citizen of the United States, residing in Rutherford, in the county of Bergen and State of New Jersey, have invented certain new and useful Improvements in Typewriting Machines, of which the following is a specification.

This invention relates to types for a machine for typewriting Japanese katakana characters, each of which usually represents a complete syllable. This application is mainly a division of my application, Serial No. 617,912, filed February 9, 1923.

15 These syllables are usually written one beneath another down the page, whereby a single word may be represented by a large number of syllables or units which are thus dissociated from one another and make 20 multi-syllable words difficult to read.

An object of the present invention is to modify the katakana alphabet with a view to avoiding the necessity of laboriously spelling out the syllables.

25 The novel font of type is designed with a view to either printing or typewriting the characters or syllables in a horizontal line from left to right, the characters closely spaced in groups, each group separated by a 30 space from the next group, so that each group may form a complete word, which can be easily grasped or read as a unit by the eye, as is commonly done in reading English and other European languages. To this 35 end, the katakana letters have been re-designed, simplified, re-proportioned and improved, for the purpose of enabling them to coalesce or harmonize for word-reading. In effecting this improvement, however, the 40 distinctive characteristics of the katakana letters, which appeal to the eye of the reader, have not been altered. One difficulty with reading ordinary katakana syllables arises from the fact that those strokes which 45 extend from left to right are given various inclinations. Downward strokes also have incongruous inclinations. In devising the 50 improved font of type embodying this invention, the right to left strokes are harmonized, and a similar course is taken with downward strokes, without altering the essential appearance of any character, the

novel letters appealing to the eye and being instantly recognizable without effort. By harmonizing the letters so that the complete 55 words themselves can be instantly read as units, the tedious process of spelling out words from syllabic units is avoided, and much time is gained, inasmuch as the eye becomes accustomed to the appearance of an 60 entire word, and no time is spent in mentally piecing syllables together.

Other features and advantages will hereinafter appear.

The accompanying drawings show the improved design for alphabet of katakana, or the types for typing or otherwise printing the same.

The katakana letters have been re-designed, re-proportioned and improved with 70 a view to giving them a pleasing and acceptable appearance.

In the accompanying drawings, the first five lines of characters correspond with the following English letters and groups:

A I U E O KA KI KU KE
KO SA SHI SU SE SO TA CHI TSU
TE TO NA NI NU NE NO HA HI
FU HE HO MA MI MU ME MO YA
YU YO RA RI RU RE RO WA N

65 The sixth line contains the characters WI WE WO and the small characters A I U E O TSU.

The seventh line contains the small characters FU HO WI WE YU YO WA MU.

66 In the last line is the dakuon for use in making the component characters GA ZA DA BA etc.

Many of the right-to-left strokes of ordinary katakana are modified by making them horizontal, and many of the ordinary up-and-down strokes are modified into vertical lines. This gives the writing a trim and elegant appearance, and the characters are given a squareness and substantiality which 75 makes them attractive and favors the reading thereof in groups.

A uniform height is established for the bodies of the letters, and the top lines of many of the letters are horizontal and extend in a single array across the page, conducting to the harmony of the characters and tending to render them easily readable in groups. The top portions of the different

characters are made distinctive, whereby the letters are readily recognized in rapid reading of horizontal lines. To secure harmony and good proportioning, many of the stems 5 are extended far above the top body lines of their characters, and some extend below the main bottom line. These extensions render it unnecessary to cramp the bodies of the letters, or give to any of them an undersized 10 appearance.

General harmony is enhanced by having uniform height in nearly all instances for the lower of two horizontal lines employed in many of the characters.

15 The two strokes of the letter NI are made horizontal, the top one agreeing with the main top line of the system, and the second one being substantially elevated above the base line of writing, but below the middle 20 of the letters. The strokes of the letter MI are also horizontal, the third stroke agreeing with the horizontal base line of the system of characters. The letters NI and MI are further embellished by means of terminal 25 dots, one being formed at the right-hand end of the top stroke, and the other at the left-hand end of the bottom stroke. This distinguishes them from the Japanese characters for 2 and 3, and also makes them 30 more easily read and more distinguished and elegant.

Dots are also used at the upper ends of SO and NO and at the lower ends of SHI and N, for giving these characters added 35 distinction and elegance, and enhancing the attractiveness of the page of typewriting or print.

Broadly curved corners are used in the 40 place of angular corners in many of the letters. Many of the characters are otherwise modified from the ordinary katakana, in order to harmonize them with one another and give distinction and lend attractiveness to the page of print.

45 The types are shown as having substantially uniform width, for typewriting purposes. The invention is also useful for ordinary printing, in which the width of the characters does not need to be uniform.

50 The dakuon shown in the last line occupies a uniform position in relation to the main characters, one of which is shown, for example KI, in dotted lines. This dakuon mark is placed so that it will clear characters 55 on both the left hand and right hand thereof, and it is curved towards the left to indicate clearly to which character it belongs.

The small characters in the sixth and seventh lines are adapted to a well-known use in 60 writing katakana, and are made of harmonious proportions and are distinctive and add to the elegant appearance of the printed page. They correspond to the main characters in width, and are a little over half as 65 tall.

Variations may be resorted to within the scope of the invention, and portions of the improvements may be used without others.

Having thus described my invention, I claim:

1. A system of Japanese katakana types in which the right-and-left strokes are made substantially all horizontal, and in which the upper horizontal strokes are in line for substantially all the characters. 70 75

2. A system of Japanese katakana types in which the right-and-left strokes are made substantially all horizontal, and in which the upper horizontal strokes are in line for substantially all the characters, the vertical 80 stems of many of the characters extending above their top horizontal lines. 85

3. A system of Japanese katakana types in which the right-and-left strokes are made substantially all horizontal, and in which the upper horizontal strokes are in line for substantially all the characters, the vertical 90 stems of many of the characters extending above their top horizontal lines, the characters having a square appearance, and the bodies having substantially uniform height. 95

4. A system of Japanese katakana types in which the right-and-left strokes are made substantially all horizontal, and in which the upper horizontal strokes are in line for substantially all the characters, the vertical 100 stems of many of the characters extending above their top horizontal lines, and some of the stems extending below the main bottom line of the characters. 105

5. A system of Japanese katakana types in which the right-and-left strokes are made substantially all horizontal, and in which the upper horizontal strokes are in line for substantially all the characters, the two horizontal lines employed in many of the characters being of substantially uniform height. 105

6. A system of Japanese katakana types in which the right-and-left strokes are made substantially all horizontal, and in which the upper horizontal strokes are in line for substantially all the characters, the two strokes of the letter NI being horizontal, the top one agreeing with the main top line 110 of the system, and the second one being substantially elevated above the line of writing. 115

7. A system of Japanese katakana types in which the right-and-left strokes are made substantially all horizontal and in which the upper horizontal strokes are in line for substantially all the characters, the two strokes of the letter NI being horizontal, the top one agreeing with the main top line of the system, and the second one being substantially elevated above the line of writing, 120 the letters NI and MI being embellished by means of terminal dots. 125

8. A system of Japanese katakana types in which the right-and-left strokes are made 130

- substantially all horizontal, and in which the upper horizontal strokes are in line for substantially all the characters, the two strokes of the letter NI being horizontal, the 5 top one agreeing with the main top line of the system, and the second one being substantially elevated above the line of writing, the letters NI and MI being embellished by means of terminal dots, one dot being formed 10 at the right-hand end of the top stroke of each of said letters, and the other at the left-hand end of the bottom stroke, to distinguish them from the Japanese characters for 2 and 3.
- 15 9. A system of Japanese katakana types in which the right-and-left strokes are made substantially all horizontal, and in which the upper horizontal strokes are in line for substantially all the characters, dots being 20 used at the upper ends of SO and NO and at the lower ends of SHI and N.
- 10 10. A system of Japanese katakana types in which the right-and-left strokes are made substantially all horizontal, and in which 25 the upper horizontal strokes are in line for substantially all the characters, the two strokes of the letter NI being horizontal, the top one agreeing with the main top line of the system, and the second one being sub- 30 stantially elevated above the line of writing, the letters NI and MI being embellished by means of terminal dots; dots being used at the upper ends of SO and NO and at the lower ends of SHI and N.
- 35 11. A system of Japanese katakana types in which the right-and-left strokes are made substantially all horizontal, and in which the upper horizontal strokes are in line for substantially all the characters, broadly 40 curved corners being used in place of angular corners in most of the letters.
12. A system of Japanese katakana types in which the right-and-left strokes are made substantially all horizontal, and in which 45 the upper horizontal strokes are in line for substantially all the characters, broadly curved corners being used in place of angular corners in most of the letters, and the characters being generally modified from the 50 ordinary katakana to harmonize them with one another.
13. A system of Japanese katakana types in which the right-and-left strokes are made substantially all horizontal, and in which 55 the upper horizontal strokes are in line for substantially all the characters, and a dakuon mark connected to a silent key, said mark so placed that it will print at the right upper part of the previously typed letters 60 so as to clear characters on both the left hand and right hand, and curved towards the left to indicate to which character it belongs.
14. A system of Japanese katakana types 65 in which the right-and-left strokes are made substantially all horizontal, and in which the upper horizontal strokes are in line for substantially all the characters, and a series of undersized characters corresponding to the main characters in width and form 70 and a little over half as tall.
15. The improvement in katakana characters and types therefor, comprising making substantially all of the right-to-left strokes horizontal with the top horizontal 75 strokes nearly all in alignment, and making nearly all the stems of the stem characters vertical, to give the characters an erect and rectangular appearance, and making the characters consist mainly of horizontal 80 strokes with vertical strokes of next highest frequency to produce a square substantial appearance and to favor combining the letters into units for typing a line from left to right, with the bodies of the letters of 85 uniform height.
16. The improvement in katakana characters and types therefor, comprising making substantially all of the right-to-left strokes horizontal with the top horizontal 90 strokes nearly all in alignment, and making nearly all the stems of the stem characters vertical, to give the characters an erect and rectangular appearance, and making the characters consist mainly of horizontal 95 strokes with vertical strokes of next highest frequency to produce a square substantial appearance and to favor combining the letters into units for typing a line from left to right, with the bodies of the letters of 100 uniform height; certain of the characters having bottom horizontal lines, most of these horizontal lines coinciding with the base line of the typing or printing, and the tops of the characters being rendered distinctive mainly by extending stems above the tops of the bodies of the letters O, KA, 105 KI, SA, SE, CHI, TO, NA, HI, YA, and curving stems downwardly to the left beyond the base line of the body letters of 110 the characters RI and WO; the top and bottom extensions rendering it unnecessary either to cramp the bodies of the letters or to give any of them an undersized appearance, said bodies having full and uniform 115 proportions.
17. The improvement in katakana characters and types therefor, comprising making substantially all of the right-to-left strokes horizontal with the top horizontal 120 strokes nearly all in alignment, and making nearly all the stems of the stem characters vertical, to give the characters an erect and rectangular appearance, and making the characters consist mainly of horizontal 125 strokes with vertical strokes of next highest frequency to produce a square substantial appearance and to favor combining the letters into units for typing a line from left to right, with the bodies of the letters of 130

uniform height, the points being placed horizontally in the characters SHI and N and vertically in the letter TSU.

18. The improvement in katakana characters and types therefor, comprising making substantially all of the right-to-left strokes horizontal with the top horizontal strokes nearly all in alignment, and making nearly all the stems of the stem characters vertical, to give the characters an erect and rectangular appearance, and making the characters consist mainly of horizontal strokes with vertical strokes of next highest frequency to produce a square substantial appearance and to favor combining the letters into units for typing a line from left to right, with the bodies of the letters of uniform height, the points being placed horizontally in the characters SHI and N and vertically in the letter TSU, and diagonally in the letter SO.

19. The improvement in katakana characters and types therefor, comprising making substantially all of the right-to-left strokes horizontal with the top horizontal strokes nearly all in alignment, and making nearly all the stems of the stem characters vertical, to give the characters an erect and rectangular appearance, and making the characters consist mainly of horizontal strokes with vertical strokes of next highest frequency to produce a square substantial appearance and to favor combining the letters into units for typing a line from left to right, with the bodies of the letters of uniform height, the points being placed horizontally in the characters SHI and N and vertically in the letter TSU, the upper point in the letter SHI coinciding with the top line of the bodies of the characters, but the body of said letter SHI terminating at a point substantially below said top line.

20. The herein-described improvements in katakana characters and types therefor, comprising the character N beginning with an integral dot at its lower left-hand end and curving upwardly to the right from said dot to a point substantially below the top body line of the remaining characters.

21. The herein-described improvements in katakana characters and types therefor, comprising the character N beginning with an integral dot at its lower left-hand end and curving upwardly to the right from said

dot to a point substantially below the top body line of the remaining characters, and having a horizontal point above the dot and below the top of the character.

22. The improvement in katakana characters and types therefor, comprising making substantially all of the right-to-left strokes horizontal with the top horizontal strokes nearly all in alignment, and making nearly all the stems of the stem characters vertical, to give the characters an erect and rectangular appearance, and making the characters consist mainly of horizontal strokes with vertical strokes of next highest frequency to produce a square substantial appearance and to favor combining the letters into units for typing a line from left to right, with the bodies of the letters of uniform height, the points being placed horizontally in the characters SHI and N and vertically in the letter TSU, the points for TSU extending from the top of the character downwardly.

23. The improvement in katakana characters and types therefor, comprising making substantially all of the right-to-left strokes horizontal with the top horizontal strokes nearly all in alignment, and making nearly all the stems of the stem characters vertical, to give the characters an erect and rectangular appearance, and making the characters consist mainly of horizontal strokes with vertical strokes of next highest frequency to produce a square substantial appearance and to favor combining the letters into units for typing a line from left to right, with the bodies of the letters of uniform height, broadly curved corners being used in the characters A, U, KA, KU, KO, SU, TSU, TA, NU, NE, HI, MA, MU, YA, YO, RO and WA.

24. A system of Japanese katakana types in which the right-and-left strokes are made substantially all horizontal, and in which the upper horizontal strokes are in line for substantially all the characters, the two strokes of the character HA beginning at the top line of the characters and diverging downwardly therefrom to points substantially above the bottom line of the characters.

BURNHAM C. STICKNEY.
